FIG. 1 is a top, front, left side perspective view of a combined electronic device charger and stand.

FIG. 2 is a right side view thereof.

FIG. 3 is a left side view thereof.

FIG. 4 is a front view thereof.

FIG. 5 is a rear view thereof.

FIG. 6 is a top view thereof; and,

FIG. 7 is a bottom view thereof.

The broken lines having equal segments represent portions of the article that form no part of the claimed design.
